UNITED STATES PATENT OFFICE.

GILBERT A. HASLUP, OF LAUREL, MARYLAND.

DESIGN FOR WALL-COVERING.

44,127.

Specification for Design.

Patented June 3, 1913.

Application filed February 16, 1911. Serial No. 609,074. Term of patent 14 years.

To all whom it may concern:

Be it known that I, GILBERT A. HASLUP, a citizen of the United States, residing at Laurel, in the county of Prince Georges and State of Maryland, have invented a new, original, and ornamental Design for Wall-Coverings, of which the following is a specification, reference being had to the accompanying drawing, forming part thereof.

In the drawing illustrating the design, the figure represents a face view of a section of wall covering showing the design.

I claim—

The ornamental design for a wall covering, as shown.

GILBERT A. HASLUP.

Witnesses:

HUGH M. STERLING,
JOHANNA GLOETZNER.
